BEDSPREAD

Jacques M. Schloss, Greensboro, N. C., assignor
to Scotland Mills, Incorporated, Laurinburg,
N. C., a corporation of North Carolina

Application September 17, 1949, Serial No. 5,060

Term of patent 14 years

(Cl. D92—2)

To all whom it may concern:

Be it known that I, Jacques M. Schloss, a citizen of the United States of America, residing at Greensboro, county of Guilford, State of North Carolina, have invented a new, original, and ornamental Design for a Bedspread, of which the following is a specification, reference being had to the accompanying drawing, forming a part hereof.

I claim:

The ornamental design for a bedspread, as shown.

JACQUES M. SCHLOSS.
